CLARENCE D. DOUTY, OF ALTOONA, PENNSYLVANIA, ASSIGNOR TO McCORD & COMPANY, OF CHICAGO, ILLINOIS, A CORPORATION OF NEW JERSEY.

OIL-FEED-CONTROLLING MECHANISM.

1,219,812.

Specification of Letters Patent. Patented Mar. 20, 1917.

Application filed July 5, 1913. Serial No. 777,556.

To all whom it may concern:

Be it known that I, CLARENCE D. DOUTY, a citizen of the United States, residing at Altoona, in the county of Blair and State of Pennsylvania, have invented certain new and useful Improvements in Oil-Fee-Controlling Mechanism, of which the following is a specification.

The invention relates to means for controlling the forced oil feed to steam cylinders, the invention being illustrated as applied to the steam chest of a locomotive, but being capable of use with other types of engines. The invention has for its primary objects, the provision of an oil feed controlling device by means of which the feed is made to occur intermittently but uniformly and with a minimum variation in oil line pressure; the provision of a controlling means whereby changes of steam chest pressure do not vary the oil line pressure; and the provision of a simple and efficient controlling means easily regulated to secure the desired feed, and which will not stick or get out of adjustment by reason of engine vibration or other cause. One embodiment of the invention is illustrated in the accompanying drawings wherein—

Figure 1 is a general arrangement view showing the front end of a locomotive with my improved apparatus applied thereto, Fig. 2 is a section on an enlarged scale through the controlling means, and Fig. 3 is a section on an enlarged scale, through a modified form of controlling means which may be substituted for that of Fig. 2.

Referring first to Fig. 1, 1 is the locomotive cylinder upon which is mounted a steam chest 2; 3 is the oil pump which is mounted upon the steam chest and may be of any approved type; 4 is the discharge pipe leading from the pump, and through which the oil is forced; 5 is the casing of the controlling device; and 6 is the shaft which drives the pump 3. The shaft 6 is driven from the cross head 7 carried by the piston rod 8 of the valve. This drive includes the usual swinging arm 9 having the usual pawl and ratchet and gear connection with the shaft 6 and lying in the casing 10.

The pump supplies the oil under pressure through the pipe 4 to the controlling device shown in section in Fig. 2. The lower portion of the casing 11 is screwed into the top

of the steam chest and is provided with the passage 12 leading from the chamber 13 to the interior of the steam chest. Oil is supplied under pressure to the chamber 13 from the pipe 4. Mounted across the upper side of the chamber 13 is a diaphragm 14 held in place by the ring 15 with which the lower edge of the casing 5 engages. The member 16 slidably mounted in the casing 5 bears upon the upper face of the diaphragm 14, and is normally held in the position indicated, by the spring 17. The lower side of the member 16 is recessed, and screw-threaded into the recess is the plug 18 which serves to clamp the inner edge of the diaphragm, a washer 19 being interposed between the face of the plug and the diaphragm. Extending through the plug is a pin or needle valve 20, such pin being fitted so as to have a slight end movement in the plug and also a slight lateral movement, in order to permit the proper seating of the valve upon its seat in case the parts are not exactly alined. A light spring 21 serves to hold the valve 20 in its upper position. The tension of the spring 17 may be adjusted by means of the screw plug 22, such plug being covered by the removable cap 23.

Assuming that the maximum steam pressure in the steam chest and cylinder is about 200 pounds, the spring 17 would be adjusted so that the pressure of the oil in the chamber 13 necessary to move the diaphragm upward and open the valve 20 would be about 275 pounds. When the pressure in the pipe line 4 produced by the oil pumps reaches a pressure of 275 pounds per square inch the valve 20 is opened, permitting a charge of oil to flow down through the passage 12 and into the steam chest and cylinder. This of course causes a reduction of pressure in the chamber 13, since the capacity of the oil pump is not sufficient to maintain the pressure in the chamber 13 at 275 pounds when the outlet 12 is open, and as a result the spring 17 causes a closure of the valve 20 when the pressure in the chamber 13 has dropped about 20 pounds. As soon as the valve 20 is closed the pressure commences to build up again in the chamber 13, and when the pressure reaches the 275-pound point the valve 20 opens again. This cycle is repeated as long as the piston 8 is reciprocated and the drive shaft 6 rotated, the operation of the pump of

course ceasing when the engine stops. The length of the pin 20 and the tension of the spring 17 are preferably so adjusted that a charge of oil is admitted for each stroke of the piston, and the amount of oil admitted is just sufficient to give the desired amount of lubrication.

It will be seen from the foregoing that the controlling mechanism provides a means whereby small charges of oil are intermittently forced into the cylinder, the number of such charges being proportional to the speed at which the locomotive is running. The area of the valve 20 exposed to pressure from the steam in the passage 12 is so slight that the changes of steam pressure do not affect the pressure in the chamber 13 at which the diaphragm moves up to open the valve. As a result, the uniformity with which the device operates is not affected by the wide variations of steam pressure in the steam chest. The increases and decreases in steam pressure in the cylinder and steam chest neither accelerate nor retard the operation of the valve 20, and as a result the cylinder is supplied with uniform charges of oil at equal intervals, the intervals of course varying with the speed of the locomotive. Various other advantages incident to the apparatus will be readily apparent to those skilled in the art.

Fig. 3 illustrates in cross section a modification of the device shown in Fig. 2, such device differing primarily from the construction of Fig. 2 in that the pressure actuated abutment is a piston instead of a diaphragm. In the construction illustrated in this figure, 24 is the inlet connected to the oil line, and 25 is the passage leading from the chamber 26 to the steam chest. The pin valve 27 is carried by the piston 28 which takes the place of the diaphragm 14 in the construction of Fig. 2. This piston is recessed interiorly and slidably mounted upon the collar 29 carried by the casing 30, packing rings 31 being employed to make a tight joint between the interior of the piston and the collar 29. The piston is normally held in its lowest position with the valve 27 closing the passage 25, by means of a spring 32 adjusted upon the plug 33. A cap 34 is screwed upon the upper end of the plug 33 and serves as a nut lock and protector for such plug. A portion of the oil pressure in the chamber 26 is exerted downward, tending to close the piston, so that the spring 32 may be made lighter than the spring 17 in the construction of Fig. 2. The spring 32 is adjusted so that the piston will move up and open the valve 27 at about the same pressures as recited in connection with the structure of Fig. 2, and the operation throughout is the same as heretofore described in connection with the device of Fig. 2. The use of the piston 28 instead of

the diaphragm 14 permits of a longer stroke of the valve 27 than is the case with the valve 20 of Fig. 2. Various other embodiments of the invention might be made, which invention broadly considered involves the provision of an abutment actuated by the oil pressure and controlling a valve which performs the double function of cutting off the line from steam pressure, and of regulating the flow of oil from the oil line to the steam cylinder. The term "cylinder" is used throughout in its generic sense, to indicate a steam receptacle whether circular in cross section or not, carrying either a valve or a steam actuated member or a piston. In the construction illustrated the steam chest 2 may be regarded as the cylinder, or the member 1 may be regarded as the cylinder, since the supply of oil from the controlling mechanism actually passes to the interior of the cylinder 1 after passing through the steam chest.

What I claim is—

1. In a forced feed lubricator for a steam cylinder, an oil pump, an oil discharge connection leading therefrom, and a controlling means for the discharge connection comprising a chamber connected to the discharge connection and to the cylinder, a valve controlling the connection from the chamber to the cylinder, a movable abutment exposed to the pressure of the oil in the chamber but cut off by the valve from pressure from the cylinder and adapted to open the valve when the oil pressure rises to a predetermined point in excess of the steam pressure in the cylinder, and a spring for holding the abutment in position to close the valve until the oil pressure in the chamber rises to the said predetermined point, the area of the valve exposed to the steam being relatively so small that the opening force applied to the valve by the steam is negligible as compared with the closing force exerted upon the valve by the spring. 100

2. In a forced feed lubricator for a steam cylinder, an oil pump, an oil discharge connection leading therefrom, and a controlling means for the discharge connection comprising a chamber connected to the discharge connection and to the cylinder, a movable abutment exposed to the pressure of the oil in the chamber, a valve operated by the abutment and controlling the connection from the chamber to the cylinder, and a spring for holding the abutment in position to close the valve and cut off communication between the cylinder and the abutment, the pressure of the spring being such that the pressure of the oil in the chamber must be in excess of the steam pressure in the cylinder in order to move the abutment to open the valve, and the area of the valve exposed to the steam being relatively so small that the opening force applied to the valve by the 125

steam is negligible as compared with the closing force exerted upon the valve by the spring.

3. In a forced feed lubricator for a steam cylinder, an oil pump, an oil discharge connection leading therefrom and a controlling means for the discharge connection comprising a movable abutment exposed to the pressure of the oil in the connection, a valve 10 operated by the abutment and controlling the flow of oil to the cylinder, and a spring for holding the abutment in position to close the valve and cut off communication between the cylinder and the abutment, the 15 pressure of the spring being such that the pressure of the oil in the connection must be in excess of the steam pressure in the cylinder in order to open the valve, and the valve when closed cutting off communication 20 from the abutment to the cylinder, the area of the valve exposed to the steam being relatively so small that the opening force applied to the valve by the steam is negligible as compared with the closing force exerted upon the valve by the spring.

4. In a forced feed lubricator for a steam-cylinder, an oil pump, an oil discharge connection leading therefrom and a controlling means for the discharge connection comprising 30 a chamber connected to the cylinder by a relatively small passage and to the said connection, a movable abutment exposed to pressure of the oil in the chamber, a pin valve operated by the abutment and controlling the said relatively small passage, and a spring for holding the abutment in position to close the valve and cut off communication between the cylinder and the abutment until the oil pressure in the chamber rises to a predetermined point in excess 40 of the steam pressure in the cylinder.

5. The combination with a machine having a part to which oil must be fed against a variable fluid back pressure, of a pump 45 driven from said machine, an oil conduit leading from said pump to said part to be lubricated, and a valve mechanism controlling the oil discharge from said conduit and including yielding means operative to close 50 said valve mechanism in opposition to a predetermined oil pressure that at least equals the maximum variable fluid back pressure, but operative to open under working oil pressure that exceeds said predetermined pressure, whereby the oil will start when 55 said machine starts and will stop when said machine stops.

6. The combination with a machine having a part to which oil must be fed against 60 a variable fluid back pressure, of a pump driven from the machine, an oil conduit

leading from said pump to said part to be lubricated, valve mechanism having a part controlling the oil discharge from said conduit and another part, on which the pressure 65 of the oil in the conduit acts to open the valve, said latter noted part being normally cut off, by the first-noted part, from materially effective back pressure, and yielding means operative to close said valve mechanism in opposition to a predetermined oil pressure that at least equals the maximum variable fluid back pressure, but permitting the same to open under working oil pressure that exceeds said predetermined pressure. 70

7. The combination with a machine having a cylinder to which oil must be fed against a variable fluid back pressure, of a pump driven from said machine, an oil discharge conduit leading therefrom, controlling means for said discharge conduit comprising a chamber connected to said discharge conduit and to said cylinder, valve mechanism having a part controlling the connection from said chamber to said cylinder and another part exposed to the pressure of the oil in said chamber, said last-noted part being normally cut off from materially effective back pressure from the cylinder, by said first-noted part of the valve 90 mechanism, and yielding means operative to close said valve mechanism in opposition to a predetermined oil pressure that at least equals the maximum variable fluid back pressure, but permitting the same to 95 open under working oil pressure that exceeds said predetermined pressure.

8. In a forced feed lubricator for an engine cylinder, an oil pump, an oil discharge conduit leading therefrom, controlling means 100 for said discharge conduit comprising a chamber connected to said discharge conduit and having a passage leading to the cylinder, valve mechanism having a part controlling said passage and another part exposed to the 105 pressure of the oil in said chamber and conduit, but normally cut off from materially effective back pressure from the cylinder, by the first-noted part, and a spring for normally holding the valve closed with a pressure 110 that at least equals the maximum variable fluid back pressure from the cylinder, but permitting said valve mechanism to open under working oil pressure that exceeds said predetermined pressure. 115

In testimony whereof I have hereunto signed my name in the presence of the two subscribed witnesses.
